CLAIM

The ornamental design for a modular, reconfigurable educational sculpture, as shown and described.

DESCRIPTION

FIG. 1 is an exploded perspective view of a modular reconfigurable educational sculpture showing my new design;

FIG. 2 is a perspective view thereof, in a fully assembled condition;

FIG. 3 is an exploded perspective view of FIG. 1, the pieces in an alternative arrangement; and,

FIG. 4 is a perspective view of FIG. 3, in a fully assembled condition.
